The ornamental design for a combined disc recorder and hard disc drive, as shown and described.

CLAIM

FIG. 1 is a perspective view of a combined disc recorder and hard disc drive showing my new design.

FIG. 2 is a front elevational view thereof;

FIG. 3 is a left side elevational view thereof;

FIG. 4 is a right side elevational view thereof; and

FIG. 5 is a top plan view thereof.

FIG. 6 is a bottom plan view thereof; and,

FIG. 7 is a rear elevational view thereof.

Portions shown as broken lines are for illustrative purpose only and form no part of the claimed design.
